UNITED STATES PATENT OFFICE.

ARTHUR L. RUSSELL, OF HYDE PARK, MASSACHUSETTS, ASSIGNOR TO UNITED SHOE MACHINERY COMPANY, OF PATERSON, NEW JERSEY, A CORPORATION OF NEW JERSEY.

HEEL-LASTING MACHINE.

1,132,978.

Specification of Letters Patent. Patented Mar. 23, 1915.

Application filed February 29, 1912. Serial No. 680,575.

To all whom it may concern:

Be it known that I, ARTHUR L. RUSSELL, a citizen of the United States, residing at Hyde Park, in the county of Norfolk and State of Massachusetts, have invented certain Improvements in Heel-Lasting Machines, of which the following description, in connection with the accompanying drawings, is a specification, like reference characters on the drawings indicating like parts in the several figures.

This invention relates to machines for use in the manufacture of shoes and is embodied in a machine for assembling shoes and lasting the heel seat portions of the shoes.

An important feature of this invention consists in a novel organization of shoe assembling and shaping apparatus. Shoe upper materials require to be properly arranged relatively upon a last and to be maintained in correctly adjusted relation while being shaped to the last.

It is one object of this invention to combine suitable devices and mechanisms by which assembling and subsequent shaping and securing operations can be carried on expeditiously, without loss of adjustment, preferably with one handling of the shoe, and with such opportunity for the exercise of skill and judgment on the part of the operator in dealing with each shoe as is desirable for the best shoe making results.

Another feature of the invention consists in an improved shoe assembling jack. The jack is herein shown as employed to support a last and shoe materials while said materials are being arranged and to tension and hold the upper in position for shaping operations upon the heel portion of the shoe. The jack shown is therefore provided with a last holder and with a gripper by the aid of which the upper can be tensioned. The gripper is preferably so constructed and arranged that the upper can be conveniently positioned in the gripper jaws and held by the jaws with the tip seam located in desired angular relation to the last during the tensioning and the heel shaping operations. In the illustrated construction the jaws are proportioned to extend across the forepart of the shoe from one lateral edge to the other and are curved in the direction of the transverse curvature of the last for seizing the upper at the tip line.

A further important feature of the inven-

tion consists in novel means for shaping upper materials to the side faces of the last. This is shown as embodied in tools constructed and arranged to engage opposite sides of the heel portion of a shoe and advance in contact with the upper materials from the rear portion of the heel toward the shank in a way to conform said materials to the contour of the side faces of the last. Preferably there is combined with said tools means for clamping the materials about the heel portion of the last. As shown the upper tensioning means co-operates with the shaping means by holding the upper under tension for the action of the shaping means. The shaping means may advantageously be carried by the jack.

Another feature of this invention consists in a novel heel seat forming mechanism. This mechanism is shown as comprising a power driven shaping roll and manually operated devices for controlling the pressure of the roll and for tilting the roll to vary the pressure upon opposite edges of the heel seat. Means is also provided for advancing and retracting the roll over the heel seat, and for holding the jack against displacement by any of the movements of the roll.

A further feature of the invention consists in the combination with upper shaping mechanism such, for example, as heel seat forming means and means operating to shape the upper to the side faces of the last, or either of such means, of a tacker and a jack movable to carry the shoe from the field of operation of the shaping mechanism into the field of operation of the tacker. In the drawings the jack upon which the shoe is assembled and the upper is tensioned is confined in a three station guide in which it has freedom of movement during the assembling operation, is maintained rigid against depression and against movement lengthwise of the shoe in the field of operation of the seat shaping roll, and is held yieldingly upraised and permitted turning movement in the field of operation of the tacker.

These and other important features of the invention, together with certain combinations of parts and useful details of construction will appear more fully from the following description of the illustrated embodiment of the invention and will then be pointed out in the claims.

Figure 1 is a perspective view of the ma-

chine; Fig. 2 is a side elevation; Figs. 3 and 4 are plan views showing successive stages; Fig. 5 is a vertical section through the mechanism shown in Fig. 6; Fig. 6 illustrates in plan the operation of conforming the upper materials to the sides of the last; Fig. 7 is a transverse section showing the grippers; Fig. 8 is a development of the heel seat former and shows in dotted lines a shoe in position for treatment to beat and wipe the upper materials downwardly and inwardly simultaneously from opposite sides of the heel toward the middle and forwardly; Fig. 9 is a view of the shoe while the grippers are pulling, the directions of the strains on the upper being indicated by arrows.

The machine comprises the post 2 which supports all the operating parts including the spindle 4 which rests by its ball end in a spring seat 5 in a pocket near the base of the post. The spindle is confined within a triangular loop 6 projecting from the side of the post and having three forks 7, 8 and 9 in the latter of which the spindle rests normally by gravity in a forwardly tipped position. A collar 10 is threaded upon the spindle to rest on the top face of the loop when the spindle is in any one of the forks and give vertical rigidity to the spindle. A hand wheel 12 also threaded upon the spindle gives adjustable support for the jack which includes the bar 15 and lever 16 on the rear side thereof. The bar 15 has a last pin 18 adjustable in its upper end by a partially inclosed nut 19 and has a forwardly extending arm 20 that is forked and between the sides of which slides a pincer. The pincer comprises inner and outer jaws 24, 25 the former of which forms the toe rest for the last and is curved and extended laterally into crescent shape conforming to the contour of the last in cross section at the tip line of the upper as shown in Figs. 1, 2 and 7. The outer jaw is of similar shape and constitutes a gage by which to position the tip seam of the upper angularly with relation to the median longitudinal axis of the last before the upper is tensioned or in any way fastened, and while therefore it is freely shiftable into correct position.

The outer gripper jaw 25 is fast on the carriage which slides between the forks of the arm 20 and has an upper guide member 26 and a lower guide member 28. The inner jaw is formed on a lever 30 which extends upwardly and forwardly from the jaw within the upper and thence downwardly and backwardly, as shown in the drawings, to its fulcrum 32 in the lower guide member 28. With the lower end of the lever 30 is connected a chain 35 which extends upwardly over a pulley in the guide member 28 to a pulley in the guide member 26 and thence over an idler in the front end

of the arm 20 and downwardly where it is connected by spring 36 to a gripper operating lever 40. This lever is pivoted to the bar 15 and has a pawl 38 to engage a segment ratchet on the bar for locking the lever 40 depressed with the upper seized and pulled and held under tension of the spring 36. A pawl lifter 39 provides for conveniently releasing pawl 38. A pawl 42 pivoted on the lower end of jaw lever 30 engages a ratchet 43 in guide member 28 to lock the jaws closed even when the lever 40 is released, as for example, to readjust the upper on the last, and a tripper 44 on arm 20 will disengage pawl 42 when the gripper is allowed to slide down the inclined arm 20 or release can be effected manually by finger pressure on the pawl 42.

The lever 16 which is pivoted to the jack bar 15 has a forwardly extending ear in a bearing in which turns a rock shaft having a hand lever 50. From this shaft depends an arm 52, Fig. 2, with a roll in a slot in the bar 15 arranged to cause downward pressure on the hand lever to draw the lever 16 and parts supported by it toward the shoe. A pawl 54 engages a ratchet face on the link to lock the lever 16 against backward movement. The head of lever 16 has a forwardly projecting lug to which forwardly extending curved arms 55 are pivotally connected. These arms carry the devices for conforming the upper materials to the side faces of the heel part of the last, including the forming tools 60 and the clamp 62. To this end the free ends of the arms 55 are formed to afford bearings for a vertical axle rod 64 upon which the tools 60 are mounted to roll, said axle rod being smaller than the holes in the rolls as appears in Figs. 4, 5 and 6. The arms also have guide bearings for spring pressed plungers 65, one for each roll, the heads of which, Figs. 5 and 6, are held by the springs 66 against the rolls to press the latter toward the shoe to the limit of the movement permitted by the difference in diameter of the rod 64 and the axle hole in the rolls. The heads of the plungers, Fig. 6, are long enough to allow the rolls to roll along them from the front to the rear as the rolls do their work. The rolls may be inclosed within a cover strap or apron 68 as in Fig. 5 which will present a continuous shoe engaging surface covering the lines between the rolls as the latter yield independently of one another as indicated in Fig. 6 to conform to the contour of the side face of the shoe. The arms 55 are pressed toward each other to cause the rolls to engage the shoe by the action of the spring plungers 69, Figs. 2, 3 and 4, which are carried by the head of lever 16 and abut against depending lips 58 of the arms as appears best in Fig. 2. In the use of these conforming tools the hand

lever 50 is manipulated to bring the lever 16 forwardly and the tools into engagement with the rear end portion of the heel and lever 50 is then vibrated to cause the rolls 60 to roll forwardly and then backwardly along the sides of the shoe as indicated by the arrows, Fig. 6, and to progress as they vibrate. In this way the stock is rolled repeatedly along the side faces of the heel to conform the upper and the heel stiffener to the contour of the underlying face of the last as the rolls yield independently of one another. Also as the operation progresses forwardly by reason of longer forward than rearward vibrations the rolls drag a little at a time, as hereinafter explained, and by their rubbing action on the upper pull the upper forwardly to tension it around the heel end of the shoe.

20 The arms 55 carry the edge clamp 62 by means of swinging bars 70, and said clamp, which comprises a steel band with a cushion lining, is resilient enough to maintain itself normally open and drawn forwardly. As the parts are moved forwardly the clamp is caused to embrace the shoe with its ends lightly following the rolls 60 as the latter reach the shank whereupon the rear end of the clamp engages the rear end of the heel which interrupts its further advance. As the lever 16 continues to advance the clamp is tightly clamped about the heel at its edge, and being narrow, the pressure of the clamp is concentrated at and just below the edge of the heel where it is most effective, while further advance of lever 16 reacts through swinging bars 70 to separate the free ends of arms 55 as in Fig. 4 and carry the rolls 60 out of contact with the shoe. In this operation the spring plungers 69 are pressed back as may be seen by comparison of Figs. 3 and 4. These plungers have headed tail rods 74 and upon these heads rests normally a bar 75 that is mounted by arms 76 to swing about a rod 77. As the heads are forced backwardly the bar 75 drops in front of them and locks the plungers with the arms 55 apart and the conforming tools 60 out of contact with the shoe for the backward movement of lever 16 when the shoe is released. This avoids any drag of the rolls rearwardly over the work. A rod 78, Fig. 2, is movable by a thumb piece 79 on a rock shaft to lift the bar 77 and free the plungers 69 and arms 55 for operation on the next shoe. The swinging bars 70 are guided over segment rails 72 on arms 55 to allow them to move easily. An adjustable stop 73 affords provision for preventing excessive forward movement of lever 16. The parts come to rest with the clamp 62 clasping the shoe firmly just below the plane of its bottom face to hold the heel stiffener from bulging away from the side of the last when the flange of it is bent down upon the heel seat. The clasp is also in position to cooperate with the heel seat forming means to shape the angular edge of the shoe where the side and bottom faces join.

25 The heel seat forming means is a roll 80 the acting face of which comprises two series of yielding beaters 82 extending obliquely inwardly from the opposite ends of the roll and backwardly with relation to the direction of rotation of the roll as will be understood from Fig. 1 and the plan or development of the roll seen in Fig. 8. This roll is constructed under United States Letters Patent to Wentworth No. 896,873 and need not be here more particularly described. Herein the roll shaft is mounted in the forked front end of a carrier rod 85 that is movable endwise and also can tip slightly in a bracket 86. This bracket has in its inner edge a guideway by which it embraces a guide rib 88 on the side of the post 2. A spring of appropriate size upholds the bracket 86 against an adjustable limit stop 89 but permits it to be pulled down by a rod connected with a treadle 90 to cause the roll 80 to act with desired pressure upon the heel seat of the shoe, the jack occupying at this time the seat 8 in loop 6. The roll shaft has at its inner end a pulley 92 engaged by a belt 94 which runs over idlers 95 carried by an arm extended from the belt carrier 85. From thence the roll runs to a continuously rotating pulley 96 loose on the power shaft of the machine. By arranging the pulley 92 and idlers 95 upon the carrier 85 the belt is maintained at substantially uniform tension in the different positions which the roll may occupy during its operation. A handled lever 100 is pivoted in a slot in the carrier rod 85 and its inner end is loosely fulcrumed between the side walls of an arc-shaped box 102. This mounting permits the roll and its carrier rod to be moved forwardly and backwardly for actuating the roll over the heel seat of the shoe and it also permits the roll and its carrier rod to be tipped about the longitudinal axis of said rod for positioning the roll with its axis parallel to the plane of the shoe bottom or for applying special pressure to one side or the other of the heel. By manipulating the lever 100 the constantly running heel seat forming roll 80 can be advanced and retracted over the shoe bottom, the pressure being regulated by the treadle lever 90. This treatment of the shoe by the seat forming roll is applied while the upper is held under forward tension to set it around the heel end of the last and the action of the roll is to draw the upper over the heel seat from opposite sides of the shoe simultaneously in lines which are directed obliquely forwardly and inwardly. The roll beats the upper down upon the heel seat progressively from the

rear end toward the breast of the heel. Both sides of the heel seat are thus progressively shaped at the same time from the rear end forwardly by sliding blows directed inwardly and forwardly from opposite edges 5 of the shoe bottom. The clasp 62 co-operates with the roll to shape the angular edge of the heel seat. When the heel seat has been satisfactorily formed and beaten until it is 10 set in lasted condition the jack is moved into the seat 9 in loop 6 where the heel seat of the shoe is under the nozzle of the tacker.

The loose pulley 96 is continuously 15 driven by a belt 105 and is mounted to slide on the shaft. A lever 106 pivoted to the head of the machine engages a collar on the pulley for effecting its sliding movements. A pull spring 108 connected to the upper 20 end of the lever and to the head draws the lever in the direction to slide the loose pulley 96 into driving engagement with a clutch member 110 fast on the shaft. A horizontal lever 112 has its lower end under- 25 lying a shoulder on the lever 106 and has a block 113 to engage laterally against the lever 106 and turn it against the pull of spring 108 to slide the loose pulley 96 out of driving engagement with the clutch 30 member 110. For disengaging said block 113 from lever 106 to permit the clutch to be closed and the tacker started the front end of the lever 112 is adapted to be lifted by a tripping device 115. This is shown in 35 the form of a bell crank lever, a lower arm of which extends into position to be engaged by the side of the shoe, or by the clamp 62, and rocked when the shoe is pressed laterally against it. A horizontal 40 arm of the bell crank actuates the lever 112 through an adjustable contact screw 116. While the tacker might be caused to run continuously as long as the shoe remains pressed against the tripper, the operator 45 turning the shoe rapidly enough to space the tacks around the heel seat, provision is herein shown for stopping the machine after the insertion of each tack and requiring a renewed pressure against the tripping de- 50 vice before another tack is driven. To this end a lever 120 carries the fulcrum for the horizontal lever 112 and the upper end of this lever 120 has a roll in a cam path of a cam block 122. This cam path is formed to 55 impart to the lever 120 and the horizontal lever 112 during each rotation of the machine a movement forwardly and then backwardly by which the block 113 of lever 112 is carried out from under the shoulder on 60 lever 106 and then moved to the left again to abut against the slide of said lever 106 and swing the latter against the pull of spring 108 to slide the continuously running pulley 96 out of driving engagement 65 with the clutch member 110.

The shaft has a cam 125 on its front end arranged to lift the driver bar 126 against the pressure of the driver spring 128. The driver cam is positioned to allow the driver to be forced downwardly by its spring im- 70 mediately after the machine is started to insert through the nozzle 130 a tack which has been fed during a previous cycle of the machine. The tacks are fed from the magazine shown in Fig. 1 through a raceway to 75 a separating mechanism which is not herein shown as these tack supplying devices form no part of the present invention. The tacker has a forked foot plate 132 against which the shoe is upheld by the spring 5 and under 80 which the shoe is moved to engage the tripping device 115. The foot plate serves as a wiper during this movement and also serves to press the upper materials firmly down upon the insole for the reception of the 85 tacks.

In the use of the machine a shoe comprising a last, innersole and upper materials, including the heel stiffener, is assembled upon the jack and there prepared for the heel seat lasting operation. It is contemplated that during this assembling operation the spindle will occupy the seat 7 in the loop 6, this seat being formed to hold the jack in stable condition with the shoe far enough away from the heel seat forming roll and the tacker to allow convenient access to all parts of the shoe. At the time the shoe is applied to the jack the arms 55 will occupy their open position as illustrated in Fig. 4 90 and the clamp 62 will also be open and together with the arms 55 retracted from the shoe so as to be out of the operator's way. This retraction of these parts is effected by releasing the pawl 54 and lifting the lever 50 whereupon the lever 16 swings backwardly by gravity to an out-of-the-way position determined by the stop 73. It will be understood from the previous description that the 95 bar 75 is the means for maintaining the arms 55 in open position against the pressure of the spring plungers 69. In applying the shoe to the jack the forepart of the upper is inserted between the open jaws 24, 25 of the toe gripper and the last rests down upon the inner jaw. The upper is positioned longitudinally about the last by locating the tip seam in symmetrical or other desired relation to the outer jaw of the grippers before the jaws are closed, the parts being so arranged that the operator can easily see the relation of the end portion of the tip seam to the end portions of the jaw on both sides of the shoe. A light pressure upon the lever 100 105 now effects closing of the jaws to grip the upper and draw it forwardly under a light tension. The operator may now inspect the shoe to make certain that the heel portion is properly positioned with relation to the heel part of the last and more particularly 110 115 120 125 130 135 140 145 150 that the marginal portion of the upper and heel stiffener extend the desired distance above the plane of the insole to allow them to be lasted in correctly, that the ends of the heel stiffener are pulled up as they should be and that the back seam of the shoe is centrally located. If the latter condition should be found not to exist then the last can be turned upon the heel pin 18 to adjust it within the upper. Such turning movement of the last may also be effected after the upper has been further tensioned, so as to prevent it from slipping about the heel portion of the last, and by this means the last and the tip seam may be relatively positioned to bring the seam at the desired angle to the longitudinal axis of the last. When the parts of the heel portion of the shoe are in proper relation the lever 40 will be depressed for stretching the upper forwardly and drawing it tight about the heel portion of the last. In this pulling operation, it will be noted that the upper at the two sides of the last is put under forward strain and that the direction of movement of the grippers on the guide arm 20 is such that the grippers are at all times on the same side of the plane of the last bottom as is the top face of the last, that is, the grippers are below the plane of the inverted last at the end of the pulling operation and therefore there is no relaxation of the tension along the marginal portion of the upper such as would occur if grippers were operated to draw the upper over upon the insole at the toe. In the latter case such slackening of the marginal portion of the upper would occur as would leave it loose around the edge of the heel portion of the last and render difficult the accurate conformation of the upper materials to the contour of the heel portion of the last. The lever 40 is locked in depressed condition by the pawl 38 so that the grippers are caused to maintain the upper in the described condition during subsequent operations on the shoe, the spring 36 serving to give a yielding quality to the tension and to effect further movement of the grippers which may be permitted by taking out additional stretch from the upper during the heel seat shaping operation. The devices for conforming the upper to the contour of the side faces of the last and further working the upper forwardly about the heel portion of the last are now brought into operation. The lever 50 is actuated to bring the lever 16 and arms 55 forwardly and when the forming tools 60 are in proper relation to the end of the heel the tripping device 79 is depressed to raise bar 75 and allow the arms 55 to close for moving the tools 60 against the shoe. As these tools engage the shoe they are allowed by the spring plungers 65 to move relatively to one another for adapting themselves to the contour of the engaged portion of the side of the last. The lever 50 may be now oscillated to move the arms 55 lengthwise of the shoe forwardly and backwardly to cause the tool 60 to conform the upper and heel stiffener to the contour of the side faces of the last by a rolling action. The forward movements will be longer than the rearward movements so as to carry on the operation progressively from the rear end of the heel forwardly toward the shank. Referring to Fig. 6, it will be understood that during the last part of each forward movement the plunger 65 and pin 64 offer considerable resistance to continue turning movements of the rolls and that the rolls are therefore caused to drag or rub forwardly thereby exerting a series of forward pulls as the operation progresses. If the apron or strap 68 is employed it forms a continuous surface covering the lines between adjacent rolls and the above mentioned forward pulling movements may be transmitted through it. As the shaping tools 60 approach the shank of the shoe the clamp 62 is drawn about the upper part of the shoe as will be understood from Figs. 3 and 4. The band adapts itself automatically to the shape and size of the shoe and when it has snugly embraced the shoe and can move no farther it becomes a fulcrum for the swinging bars which then operates to separate the swinging arms 55 thereby withdrawing the rolls 60 from contact with the shoe as shown in Fig. 4. In this latter movement the spring plungers 69 are compressed and their headed tail rods move under the bar 75 until that bar can drop down in front of the heads on said rods where it will lock the plungers 69 against advancing again. The pawl 54 will lock the lever 16 and the parts actuated thereby against reverse movement so that the clamp is caused to hold the upper securely without further attention. It will be noted that this clamp is intended to engage the shoe for a short distance only from its edge downwardly. It is therefore substantially unaffected by variations in the vertical curvature of the side faces of different lasts and serves to hold the heel stiffener securely clasped about the last just below the edge line where the stiffener tends to bulge outwardly at the time it is being bent forwardly upon the insole at the heel seat. The clamp thereby coöperates effectively with the heel seat forming means to produce a close fit of the shoe stock to the last and to produce an angular edge of the lasted shoe as distinguished from the rounded edge which there is always a tendency to form when stiff material is bent over the angular edge of a last or other form. The shoe is now ready for movement of the jack from the seat 7 to the seat 8 of the loop 6 for transferring the work into the field of operation of the heel seat forming roll 80.

As the spindle of the jack enters the seat 8 the collar 10 thereof is caused to ride on to an inclined top face 81 of the seat for rigidly upholding the shoe for the heel seat 5 lasting operation. The incline 81 takes the load and pressure instead of allowing it to be received by the spring 5. It will be noted from Fig. 1 that the seat 8 is so formed in the loop that it holds the spindle 10 against movement forwardly and rearwardly and thereby securely resists displacement of the work in the direction which the movement of the heel seat forming roll 80 over the shoe tends to displace it. The operator 15 advances the continuously running roll 80 over the shoe by movement of the hand lever 100 thereby causing the two series of beating devices 82 to act simultaneously upon the marginal edge of the shoe upper 20 materials for laying and beating them down upon the insole at opposite sides of the heel seat. The opposed angular arrangement of the two series of beating members with relation to their direction of rotation causes the 25 roll to draw the upper over the heel seat from opposite sides simultaneously in lines directed obliquely forwardly and inwardly and beat it down upon the heel seat progressively from the rear end toward the 30 breast of the heel. It is to be noted that this action takes place while the upper is under tension which pulls it forwardly to set it around the heel end of the last.

The degree of downward pressure of the 35 seat forming roll upon the work is controlled by the operator through the foot treadle 90 and the hand lever 100 affords means by which the operator can tilt the roll 80 and bring it into parallelism with the heel seats of different shoes or can concentrate the forming action on one side or on the other side of the shoe. Experience has demonstrated that this heel seat forming 40 operation will break down the upper materials upon the heel seat and draw them tightly 45 into lasted position and set them in this position so that the shoe can then be taken to a tacking machine for tacking the heel seat. The jack is now shifted to the seat 50 9 in the loop 6, the top face of said seat being in a lower plane than the incline 81 so that the weight of the jack and shoe is sustained by the spring 5. The shoe is pressed laterally against the tripping device 115 55 which through the mechanism above described causes a tack to be inserted. The operator turns the shoe to present the different tacking points under the nozzle. The lever 120 and the cam 122 effect stopping 60 of the machine after the insertion of each tack and in pressing the shoe backwardly to cause tripping of the device 115 the shoe is caused to rub under the foot plate 132 which wipes over the upper materials and 65 holds them down on the insole for the re-

ception of the tack. When as many tacks as are required have been inserted in the heel seat, the jack is moved again to the seat 7. The pawl 54 and lever 50 are lifted to disengage the clamp 62 from the shoe and then 70 the pawl 38 and lever 40 are lifted and the grippers allowed to slide down the inclined guide arm 20 until the pawl 40 strikes the tripping device 44 whereupon the grippers are opened to permit the removal of the 75 shoe from the machine. When the shoe is taken from the machine it is in assembled condition ready for presentation to a pulling-over machine and the heel seat is completely lasted. Moreover, in the assembling 80 operation, the upper may have been properly adjusted longitudinally about the last so that the shoe can be placed in the pulling-over machine and the upper seized by the grippers with fair assurance that the 85 tip seam will be properly located angularly and no tip straightening adjustment required during the upper pulling-over operation. It is contemplated that the longitudinal stretch will have been taken out 90 of the upper by the use of the described forepart grippers so that the upper stretching operation to be performed by the pulling-over machine will be reduced and simplified. This is of particular advantage 95 when shoes are being made upon lasts having high toes presenting a relatively low portion between the toe and the instep into which it is difficult for the side grippers of the pulling-over machine to draw the upper 100 down if the upper is required to be stretched by the toe gripper before the side grippers operate. Another advantage of this machine is that by seizing substantially the full width of the upper by the described toe 105 grippers and stretching the entire upper forwardly as herein explained, the shoe is more completely stretched than heretofore and it is possible to cut the shoe upper smaller than has heretofore been required, 110 thereby effecting a saving in upper stock. The operation of this machine also renders unnecessary the practice followed by many pulling-over machine operators of seizing the upper with hand pincers or with a tip 115 puller and stretching the upper forwardly in order to draw the upper down the incline of the instep and otherwise position the upper lengthwise of the last so that the toe pincer of the machine can get hold of it. 120

I am aware of the invention of B. F. Mayo described in application for United States Letters Patent filed by him February 28, 1912, Serial No. 680,450, and I claim nothing that is disclosed in that application. 125

Having explained the nature of this invention and described a preferred construction embodying the same in the best form now known to me, I claim as new and de- 130

sire to secure by Letters Patent of the United States:

1. An organized machine having, in combination, a heel seat tacker, a heel seat former, a shoe holder upon which the shoe can be prepared for the heel seat lasting operation, and means for retaining the parts of the shoe in said prepared condition, said machine being constructed and arranged to hold the shoe while being prepared out of the fields of operation of the former and the tacker and said holder and retaining means being movable to carry the shoe so prepared first into the field of operation of the heel seat former and then into the field of operation of the heel seat tacker.
2. An organized machine having, in combination, a heel seat tacker, a heel seat former, a shoe holder, and means for tensioning the upper about the heel end of the last forwardly and maintaining it under tension; said holder, tensioning means, and the shoe, and the heel seat former being relatively movable into operative relation for the heel seat forming operation, and said holder, tensioning means and shoe and the tacker being relatively movable into operative relation for the heel seat tacking operation to be performed, said tensioning means being arranged with reference to the holder to maintain the upper under tension during both said operations.
3. An organized machine having, in combination, a heel seat tacker, a heel seat former, a shoe holder, and means to effect and maintain tension of the upper about the heel end of the last, said holder and tensioning means being movable together from upper tensioning position to operative relations to the former and to the tacker for the purposes described.
4. An organized machine having, in combination, a heel seat tacker, a heel seat former, a shoe holder, and a gripper mounted on the holder and arranged to pull the upper forwardly and maintain it under tension about the edge of the heel seat; said holder and gripper being movable to carry the shoe into position to be operated upon by the heel seat former and then with the upper still under tension into operative relation to the tacker.
5. An organized machine having, in combination, a heel seat tacker, a heel seat former, a shoe holder, means to tighten the upper forwardly about the heel end of the last, and means to clamp the upper so tightened about the edge of the heel seat; said holder, former and tacker being relatively movable into operative relations for the seat forming and seat tacking operations, and said clamping means being arranged to retain its hold upon the upper during both said operations.
6. An organized machine having, in com-

bination, a heel seat former, power mechanism for operating it, a shoe holder, and means for tightening the upper forwardly about the heel end of the last while the shoe is out of operative relation to the heel seat former, said holder, together with the tightening means, being movable into such operative relation and there being provision for relatively moving the former and the shoe holder to cause the forming operation to be effected progressively from the rear end of the heel seat toward the breast end.

7. An organized machine having, in combination, a heel seat former, power mechanism for operating it, a shoe holder, a gripper movable in the shoe holder to pull the upper forwardly about the heel end of the last, and means to lock the gripper with the upper under tension, said holder and shoe, together with the grippers, being movable with the upper under tension to present the shoe to the former and being movable relatively to the former to cause the heel seat to be lasted.

8. An organized machine having, in combination, a rotary heel seat former, a shoe holder, means for tightening the upper forwardly about the heel end of the last while the shoe is out of operative relation to the heel seat former, said holder being movable into such operative relation, power mechanism arranged to rotate the former forwardly in contact with the heel seat to cooperate with the upper tightening means, and means for advancing the rotary former over the work to form the heel seat progressively from the rear end forwardly while the upper is maintained under tension by said tightening means.

9. An organized machine having, in combination, a heel seat former, power mechanism for operating it, a shoe holder, and means to tighten the upper about the heel portion of the last progressively from the rear end forwardly toward the shank, said parts being arranged to effect the seat forming operation progressively from said rear end forwardly while the upper is maintained in said tightened condition.

10. An organized heel seat lasting machine having a heel seat former, a stationary tacker, a pivoted shoe holder, a gripper on the shoe holder arranged to tension the upper forwardly about the heel end of the last and maintain it under tension, said holder and gripper being movable with the shoe to present the work to the operations of said former and tacker while maintaining the tension on the upper.

11. In an organized machine a stationary tacker, operating mechanism therefor, and a toe gripper and a last holder which are relatively movable to stretch the upper longitudinally of the shoe and are movable together to present the shoe to the tacker for

- the operation of fastening the upper in stretched and adjusted position, and means for conforming the upper materials to the heel seat face of the last after the upper is tensioned and before it is tacked.
12. An organized machine having, in combination, means for holding a last with the upper loosely applied over the top face of the forepart, upper engaging grippers operatively connected with the last holder and arranged on the same side of the plane of the last bottom as the top face of the last, means for actuating the grippers and the holder relatively for straining the upper lengthwise of the last, means for forming the strained upper over the last bottom, and means for fastening the formed upper, said grippers being arranged to maintain the upper under tension while the shoe is operated upon by said forming and fastening means.
13. An organized machine having in combination, means for holding a last, means for pulling an upper lengthwise of the last, said machine being so constructed and arranged that the last can be turned within the upper for making relative adjustment of the upper and last, and separate mechanisms for first forming and then fastening the heel seat while the upper is held in pulled and adjusted position, said machine including provision for relative movement of the last holding means and said mechanisms to present the shoe for the forming and fastening operations without disturbing the operation of the pulling means upon the upper.
14. An organized machine having, in combination, means for supporting a last for movement about a single pivotal axis located in its heel portion, means for putting the upper at the two sides of the last under lengthwise forward strain and tightening it about the heel end of the last, and means for forming the upper into lasted position on the heel seat while it is held in the condition described, said machine including provision for relative movement of the supporting and forming means without disturbing the operation of said tightening means upon the upper.
15. An organized machine having, in combination, means for supporting a last for movement about a single pivotal axis located in its heel portion, means for putting the upper at the two sides of the last under lengthwise forward strain and tightening it about the heel end of the last, and separate mechanisms for forming and fastening the heel seat while the upper is held in the condition described, said machine including provision for relative movement of the supporting and forming means without disturbing the operation of said tightening means upon the upper.
16. An organized machine having, in

combination, means for supporting a last for movement about a single pivotal axis located in its heel portion, means for putting the upper at the two sides of the last under lengthwise forward strain and tightening it about the heel end of the last, and a heel seat former and a tacker to the operation of which the shoe so held may be subjected by movement of the holder and the tightening means while the upper is held in the condition described.

17. An organized machine having, in combination, means for supporting a last for movement about a single pivotal axis located in its heel portion, means for pulling the upper in substantially straight lines over the top face of the toe of the last and holding the marginal portions of the upper at the sides of the last under tension, said parts being constructed and arranged to permit turning of the last laterally to vary the relative strains on the upper at the two sides of the shoe, and means arranged for operation while the upper is so held for conforming the upper materials to the contour of the side face of the last.

18. An organized machine having, in combination, means for supporting a last, devices having a constant connection with said support and adapted to grip the toe of the shoe upper arranged on the last, means for moving the last support and the toe gripper relatively to strain the heel portion of the upper about the heel of the last, means to guide the moving part in a path to cause the upper to be strained and maintained under tension about the side faces of the heel near its edge, means for lasting the heel seat, and laterally adjacent means into operative relation to which the shoe support may be moved from the heel seat lasting means and which can be used to tack the upper progressively around the lasted heel seat while the upper is so held by the gripper.

19. An organized machine having, in combination, a tacker, a shoe holder that is movable to carry the shoe under the tacker, and a gripper on the shoe holder that is arranged to pull the upper lengthwise of the last and to move with the holder to maintain the upper under tension while it is tacked and means for conforming the upper materials to the contour of the side face of the last while said materials are tensioned by the gripper.

20. An organized machine having, in combination, a tacker, a heel seat former, a shoe holder movable to carry the shoe under the former and then under the tacker, and a gripper on the holder arranged to pull the upper lengthwise of the last and to move with the holder to maintain the upper under tension while the heel seat is formed and tacked.

21. An organized machine having, in com-

- bination, a heel seat former comprising two series of rotary beaters arranged to act simultaneously upon the marginal edge portion of a shoe upper at opposite sides of the 5 shoe and to beat out said edge portion of the upper upon the insole, means for actuating said beaters to rub the upper forwardly from the heel end of the last, a holder for presenting the shoe to the action of the beaters, and means for holding the upper under tension over the last during the operation of said forwardly acting beaters.
22. An organized machine having, in combination, a heel seat former, comprising two 15 series of rotary beaters arranged to act simultaneously upon the marginal edge portion of a shoe upper at opposite sides of the shoe and to draw the upper over the edge of the insole toward the median line of the heel seat and forwardly toward the toe end of the shoe, means for actuating the beaters, and means for tensioning the upper about the heel portion of the last in the same forward direction as the operation of the beaters and maintaining it under tension during the 20 beating operation.
23. An organized machine having, in combination, a heel seat former comprising two series of rotary beaters arranged to act simultaneously upon the marginal edge portion of a shoe upper at opposite sides of the shoe and to draw the upper over the edge of the insole toward the median line of the heel seat, means for tacking the upper 25 after it has been beaten down, whereby the effect of the beaters is rendered permanent, and actuating mechanism for the former and the tacker.
24. An assembling and heel seat lasting machine having, in combination, a shoe 30 holder having a heel pin for the last and an arm extending forwardly under the last and a gripper movable in the arm to pull the upper lengthwise and comprising jaws proportioned to extend across the forepart of the shoe from one lateral edge to the other and curved to be transverse curvature of the last for seizing the upper at the tip line, and means for actuating the gripper and last 35 relatively to tighten the upper about the heel portion of the last.
25. An assembling and heel seat lasting machine having, in combination, a shoe holder having a heel pin for the last and an 40 arm extending forwardly under the last and a gripper movable in the arm to pull the upper lengthwise and shaped to seize substantially the entire width of the upper at the tip seam, means for actuating the gripper to 45 tighten the upper about the heel portion of the last, and means for forming the upper over upon the heel seat of the last.
26. An assembling and heel seat lasting machine having, in combination, a shoe 50 holder having a heel pin for the last and a gripper comprising jaws to engage the upper at or near the tip seam and formed and arranged to indicate the relation of the tip seam to the last, means for relatively actuating the heel pin and the gripper to tension the upper about the heel portion of the last, said parts being arranged to permit the last to be turned on the heel pin to adjust it within the upper, and means to 55 fasten the upper in tensioned and adjusted position, said holder and fastening means being relatively movable to present the shoe for the fastening operation without disturbing the operative relation of the gripper to the upper.
27. An assembling and heel seat lasting machine having, in combination, a shoe holder having a heel pin for the last and a gripper for the toe portion of the upper, means for relatively actuating the heel pin and the gripper to tension the upper about the heel portion of the last, a heel seat former, a heel seat tacker, and a pivotal support for the shoe holder permitting 60 movement to present the assembled shoe to said former and to said tacker.
28. An assembling and heel seat lasting machine having, in combination, a shoe holder upon which to assemble the shoe, a heel seat former for working the upper into lasted position upon the heel seat, a tacker for fastening the upper in lasted position, said holder being movable to present the shoe to the former and then to the tacker, the wedge 65 85 for rendering the holder rigid against downward movement when the shoe is in operative relation to the former, and means for yieldingly upholding the shoe for the action of the tacker.
29. An assembling and heel seat lasting machine comprising an assembling jack pivotally supported, a heel seat forming means, a heel seat tacking means, and a loop embracing the jack and having a seat in which to hold the jack for the assembling operation, a seat in which to hold the jack for the operation on the shoe of the heel seat forming means, and a seat to hold the jack for the operation of the tacking means.
30. An assembling and heel seat lasting machine having, in combination, an assembling jack, a heel seat forming means and a tacker, said jack comprising a tipping spindle yieldingly supported, a collar on the 100 spindle, and means operative upon said collar when the jack is in working relation with the heel seat forming means to uphold the shoe unyieldingly.
31. An assembling and heel seat lasting machine having, in combination, an assembling jack comprising a last pin, a toe gripper having curved gripper jaws 24, 25 ar-

- ranged to seize the upper at or adjacent to the tip seam and having their end portions extending into position to form gages with reference to which the tip seam may be positioned, means for actuating the gripper to pull the upper longitudinally on the last, and means arranged for working the heel seat portion of the shoe into lasted position without disturbing the operative relation to the upper of the gripper and its actuating means. 5
32. An assembling and heel seat lasting machine having, in combination, an assembling jack comprising a last pin, and a toe gripper comprising an inner jaw curved to extend across the shoe in the region of the tip seam under the last and form a seat for the last, a coöperating jaw, means for actuating the jaws to pull the upper lengthwise of the last, and means arranged for forming the heel seat of a shoe while the upper is held under tension by the jaws without disturbing the operative relation to the upper of the gripper and its actuating means. 10
33. An assembling and heel seat lasting machine comprising an assembling jack having a last pin and a combined forepart rest and inner gripping jaw arranged to extend across under the last between the last and the upper, a coöperating jaw to engage the outer side of the upper, means to actuate said jaws to pull the upper, said inner jaw serving to sustain the toe end of the last against downward movement during the pulling operation, and means arranged for forming the heel while the shoe is held by said jaws without disturbing the operative relation to the upper of the gripping jaws and their actuating means. 15
34. An assembling and heel seat lasting machine having, in combination, a shoe support, a gripper comprising jaws curved transversely of the last and arranged for operation beneath the forepart of the last to seize substantially the full width of the upper at or adjacent to the tip seam, and means for actuating said jaws to tighten the upper forwardly about the rear end of the last. 20
35. An assembling and heel seat lasting machine having, in combination, a shoe support, a gripper comprising jaws curved transversely of the last and arranged for operation beneath the forepart of the last to seize substantially the full width of the upper adjacent to the low portion of the last that is located between the instep and the high toe, and means for actuating the jaws relatively to the last to tighten the upper about the rear end of the heel and draw the upper down the instep incline. 25
36. An assembling and heel seat lasting machine having, in combination, a shoe support, forming tools arranged at opposite sides of the heel portion of the shoe, means for actuating said tools in engagement with the upper from the rear end of the shoe toward the shank to shape the upper materials to the side faces of the last, and heel seat forming means arranged for working the marginal portions of the upper into lasted position upon the heel seat portion of the insole without disturbing the operative relation of said tools to the sides of the upper. 30
37. An assembling and heel seat lasting machine having, in combination, a shoe support, forming tools arranged to engage opposite sides of the shoe, means for moving said tools in contact with the shoe stock from the rear end of the shoe forwardly to the shank to make the upper materials conform to the contour of the heel portion of the last, means for holding the upper against the side faces of the last near the heel seat, and heel seat forming means to lay the marginal portion of the upper materials down upon the heel seat of the shoe while the upper materials are so held on to the side faces of the last. 35
38. An assembling and heel seat lasting machine having, in combination, a shoe support, tools for engaging opposite sides of the shoe and movable in contact with the upper materials from the rear end of the shoe forwardly to the shank to conform said materials to the contour of the side faces of the heel, means for clamping said upper materials about the heel end of the last, and means for lasting the heel seat of the shoe while the stock is so clamped. 40
39. An assembling and heel seat lasting machine having, in combination, a shoe support, rolls arranged to engage opposite sides of the heel portion of the shoe and advance in contact with the upper materials from the rear end of the heel forwardly to conform said materials to the contour of the side faces of the last by rolling pressure, and means for lasting the heel seat while the upper is so conformed to the adjacent portions of the side faces of the last. 45
40. An assembling and heel seat lasting machine having, in combination, a shoe support, devices arranged to be advanced relatively to the shoe to conform the upper materials by yielding pressure to the side faces of the last from the rear end toward the shank, and means for automatically discontinuing said pressure preparatory to the return movement of said devices. 50
41. An assembling and heel seat lasting machine having, in combination, a shoe support, devices for conforming the upper materials to the side faces of the heel part of the last including forming tools movable longitudinally of the shoe and a clamp to embrace the heel after the operation of the tools on the stock, and means for lasting the heel seat. 55

after the stock has been so prepared, said lasting means coöperating with the clamping means to produce an angular formation of the upper materials around the edge of 5 the heel seat.

42. An assembling and heel seat lasting machine having, in combination, a shoe support, means for conforming the upper materials to the side faces of the heel part of 10 the last including forwardly extending arms yieldingly held toward the shoe and equipped with rollers to engage the side faces of the shoe and advance from the rear end toward the shank, and means for lasting the marginal portion of the upper materials over the 15 heel seat of the insole while the upper is held in said conformed relation to the last.

43. An assembling and heel seat lasting machine having, in combination, a shoe support, the swinging arms 55 yieldingly held closed, rollers 60 carried on said arms, means for relatively advancing the arms with the rollers along the shoe from the heel end toward the shank to conform the upper materials to the contour of the side faces of the 20 last by rolling pressure, and means for lasting the heel seat while the upper is held in said conformed relation to the last.

44. An assembling and heel seat lasting machine having, in combination, a shoe support, means for conforming the upper materials to the contour of the side faces of the last comprising a plurality of rolls arranged on an axis perpendicular to the shoe 25 bottom and supported for independent yielding movements at right angles to said axis to enable them to adapt themselves to the shape of the shoe as they progress over the work, and means for lasting the heel seat 30 while the upper is held in said conformed relation to the last.

45. An assembling and heel seat lasting machine having, in combination, a shoe support, means for engaging opposite sides of the heel and movable forwardly thereover to conform the upper materials to the contour of the side faces of the last, additional means arranged to embrace the heel end of the last near its edge and clamp the upper 35 materials after the operation of said forming means thereon, and heel seat lasting means to lay the upper materials down upon the inside and coöperating with said clamping means to form an angular edge about 40 the heel seat.

46. An assembling and heel seat lasting machine having, in combination, a shoe support, rolls for engaging opposite sides of the shoe to conform the upper materials to 45 the side faces of the last, and means whereby to impart to the shoe and said rolls relatively short reciprocatory movements lengthwise of the shoe and treat the stock 50 repeatedly as the rolling operation pro-

gresses from the rear end of the shoe toward 65 the shank.

47. An assembling and heel seat lasting machine having, in combination, the arms 55 held yieldingly toward each other, the rolls 60, the pivot pins 64 confining said 70 rolls on said arms and having diameters less than the openings in the rolls, and means to impart to the arms short reciprocatory movements to cause the rolls to pass over the stock repeatedly as the operation progresses. 75

48. An assembling and heel seat lasting machine having, in combination, the arms 55 held yieldingly toward each other, the rolls 60, the pivot pins 64 confining said 80 rolls on said arms and having diameters less than the openings in the rolls, and the spring pressed plungers 65 against which the rolls can yield relatively to the pivot pins.

49. An assembling and heel seat lasting machine having, in combination, the arms 55 held yieldingly toward each other, the rolls 60, the pivot pins 64 confining said 85 rolls on said arms and having diameters less than the openings in the rolls, and a strap or 90 apron embracing the acting portion of the faces of the rolls, substantially as described.

50. An assembling and heel seat lasting machine having, in combination, a shoe support, means for conforming the upper materials to the contour of the side faces of the last at the heel, and mechanism for actuating said means lengthwise of the shoe to do its work by a combined rolling and forwardly rubbing movement over the side 100 faces of the shoe.

51. An assembling and heel seat lasting machine having, in combination, a shoe support, shaping rolls movable forwardly in engagement with opposite sides of the heel, 105 and means for automatically separating said rolls to carry them out of contact with the work when they reach the limit of their forward movement.

52. An assembling and heel seat lasting machine having, in combination, a shoe support, shaping rolls movable forwardly in engagement with opposite sides of the heel, a clamp arranged to embrace the heel, and means for automatically separating the rolls 115 after the clamp comes into holding position.

53. An assembling and heel seat lasting machine having, in combination, pivoted arms carrying rolls for engaging opposite sides of the heel to conform the upper materials to the contour of the last, a heel embracing clasp, means for actuating said arms and clasp to do the work, and means connected with the clasp for spreading the arms when the clasp has come into holding 120 position.

54. An assembling and heel seat lasting machine having, in combination, swinging

arms, rollers on the arms, spring pressed plungers acting on the arms to hold the rollers to the work, a heel embracing clasp, and links connecting said clasp and arms and arranged to spread the arms when the clasp has embraced the last.

55. An assembling and heel seat lasting machine having, in combination, a clasp, means for actuating the clasp lengthwise of the shoe into heel embracing position, devices arranged to precede the clasp in contact with the upper materials and acting progressively forwardly thereover to conform the upper materials to the contour of the side faces of the last, means for moving said devices away from the shoe when the clasp has embraced it and means for locking said devices.

56. An assembling and heel seat lasting machine having, in combination, a shoe support, devices movable forwardly along the sides of the heel portion of the shoe to conform the upper materials to the contour of the last, means for pressing said devices toward the shoe while they are advanced, means for automatically moving said devices laterally away from the shoe when they reach the limit of their forward movement, and means for locking said pressing means against operation while said devices are retracted.

57. An assembling and heel seat lasting machine having, in combination, a shoe support, the swinging arms 55, the forming tools 60 carried by said arms, the spring pressed plungers 69 arranged to move said arms in the direction to hold the forming devices against the work, means for reversely moving said arms when the forming devices have done their work and thereby rearwardly actuating said plungers, the latch bar 75 arranged to lock said plungers automatically in their retracted position, and the tripping arms 79 and connections for lifting the latch bar.

58. An assembling and heel seat lasting machine having, in combination, a shoe support, a lever 16 pivoted to said support, devices carried by said lever for conforming the upper materials to the side faces of the last, the operating lever 50 and link 52 connecting said lever 16 with the last support and permitting manual reciprocation of said conforming devices.

59. An assembling and heel seat lasting machine having, in combination, a shoe support, the lever 16 pivoted thereto, the heel embracing clamp 62 carried by said lever, the operating lever 50 and connection 52 between the shoe support and lever 16 for operating the latter, and the pawl 54 for locking the parts with the clamp in operative relation to the shoe.

60. An assembling and heel seat lasting

machine having, in combination, a shoe support, a continuously running heel seat forming roll, driving mechanism for rotating said roll, and manually operated means for tilting said roll to control the relative pressure thereof upon opposite edges of the heel seat.

61. An assembling and heel seat lasting machine having, in combination, a heel seat forming roll, an assembling jack movable to carry the shoe into the field of operation of said roll, driving mechanism for rotating the roll, retaining means for holding the jack against displacement in the direction of the length of the shoe while in said relation to the roll, and manually controlled means for advancing and retracting the roll over the heel seat.

62. An assembling and heel seat lasting machine having, in combination, a heel seat forming roll, a jack having a spindle, a loop 85 having a seat shaped to confine the spindle against displacement in the direction of operative rotation of the roll and also in the opposite direction, means for rotating the roll, and means whereby to advance and retract the roll over the heel seat of the shoe.

63. An assembling and heel seat lasting machine having, in combination, a jack, a heel seat forming roll, means for turning the roll, means whereby the roll may be advanced over the heel seat, and means whereby the roll and the jack may be moved relatively to govern the pressure of the roll upon the heel seat.

64. An assembling and heel seat lasting 100 machine having, in combination, a shoe support, a heel seat forming roll, a vertically movable supporting bracket for the roll, a horizontally movable carrier by which the roll can be advanced and retracted over the 105 heel seat of a shoe, and means for turning the roll in its bearings in said bracket.

65. An assembling and heel seat lasting 110 machine having, in combination, a shoe support, a heel seat forming roll, power means 116 for turning the roll, a hand lever for advancing the roll over the heel seat while it is being turned, and a treadle for depressing the roll upon the heel seat.

66. An assembling and heel seat lasting 115 machine having, in combination, a shoe support, a heel seat forming tool, power means for turning the tool, a hand lever and connections for advancing and retracting the tool over the heel seat, said lever and connections being capable of movement for tilting the tool at right angles to its axis of rotation while it is being turned.

67. An assembling and heel seat lasting 125 machine having, in combination, a shoe support, a heel seat forming tool, a supporting bracket therefor, a carrier rod movable endwise in the bracket to advance and retract

the tool over the work and capable of turning in the bracket to tilt the tool, and a hand lever connected with said carrier rod and bracket for effecting the advancing and retracting and the tilting movements of the tool.

68. An assembling and heel seat lasting machine having, in combination, a shoe support, a heel seat forming tool comprising two series of rotating beaters adapted to act simultaneously to draw in and beat down the marginal edge of the shoe upper upon the innersole at opposite sides of the shoe, supporting means for the roll, means for turning the roll, and manually controlled means for tilting the roll and the shoe relatively to control the action of said series of beaters on the two sides of the shoe bottom.

69. An assembling and heel seat lasting machine having, in combination, a movable shoe support, a heel seat forming roll, a heel seat tacker, a driving shaft, a continuously running pulley and driving connections therefrom to the roll, a clutch connecting said pulley to the tack driving mechanism, and a tripping device for the clutch arranged to be engaged by the work as the shoe is moved into position to receive a tack for fastening the formed heel seat.

70. An assembling and heel seat lasting machine having, in combination, upper tightening means, counter shaping means arranged to operate upon the shoe subsequently to the operation of the tightening means, heel seat forming means arranged to operate after the shoe has been subjected to the action of the counter shaping means, and operating devices for actuating each of said means and directing their action on the heel portion of the upper forwardly of the last.

71. An assembling and heel seat lasting machine having, in combination, upper shaping tools to engage opposite sides of a shoe, a carrier by which said tools are moved to do their work and on which they are relatively pressed together yieldingly, locking means for discontinuing said yielding pressure, means to release the locking means, and means for automatically rendering said locking means again operative at the end of the operation of said tools.

72. An assembling and heel seat lasting machine having, in combination, upper shaping tools to engage opposite sides of a shoe, a carrier by which said tools are reciprocated to do their work progressively along the shoe, substantially as described, said tools being arranged in the carriers to roll over the work during each backward reciprocal stroke and during the return portion of the forward stroke and then to rub over the stock during the progressive portion of the forward stroke.

73. An assembling and heel seat lasting machine having, in combination, upper

shaping tools to engage opposite sides of a shoe, a carrier by which said tools are reciprocated to do their work progressively along the shoe, and a strap or apron embracing the tools and being loose enough to permit the tools to rub through it while it remains stationary relatively to the work during each backward stroke and during a part of the forward stroke and arranged to be dragged by the tools over the work by the progressing part of each forward stroke.

74. An assembling and heel seat lasting machine having, in combination, means for tightening the upper forwardly about the heel end of the last, and connected means for thereafter clamping the upper about the edge of the heel portion of the last to hold it for the heel seat lasting operation.

75. An assembling and heel seat lasting machine having, in combination, means for tightening the upper forwardly about the heel end of the last, and holding means for then clamping the upper about the end of the last near its edge only, and seat forming means to operate on the shoe while the holding means maintains the upper tightened, the machine including provision for presenting the shoe to the heel seat forming means without disturbing the operative relation of the holding means to the upper.

76. In a machine of the class described, the combination with a shoe shaping tool, of a flexible apron interposed between the tool and the shoe and through which the tool acts on the shoe.

77. In a machine of the class described, the combination with a rotatable shoe shaping tool, of a flexible apron interposed between the tool and the work and in contact with which the tool turns to act on the shoe.

78. In a machine of the class described, the combination with a rotatable shoe shaping tool, of a flexible apron interposed between the tool and the work and mounted to move during the operation of the tool in the direction of the relative progressive movement of the work.

79. In a machine of the class described, the combination with the rotatable group of tools 60 for conforming the upper and the heel stiffener to the contour of the side faces of the last, and the apron 68 forming a continuous surface covering the lines between the adjacent tools of the group and forming an intermediate member over which the tools move and through which the action of the tools is transmitted to the work.

80. An assembling and heel seat lasting machine having, in combination, means for supporting a shoe, a continuously running heel seat forming roll, means for driving said roll, and manually operated means whereby the roll may be advanced and retracted over the heel seat of a shoe on said supporting means.

81. An assembling and heel seat lasting machine having, in combination, a shoe support, a heel seat forming tool comprising two series of rotating beaters adapted to act 5 simultaneously to draw in and beat down the marginal edge of the shoe upper upon the innersole at opposite sides of the shoe, a vertically movable support for said tool, a carrier rod for the tool movable horizontally 10 in the support and adapted for turning movement to tilt the tool to vary the action of said beaters on the opposite sides of the shoe, a pulley connected with the tool, idlers on the carrier rod, a driving pulley located at a distance from the idlers, and a belt extending about said pulleys and idlers to drive the tool in any position to which it is movable. 15

In testimony whereof I have signed my name to this specification in the presence of 20 two subscribing witnesses.

ARTHUR L. RUSSELL.

WALTER BRANDT,
FREDERICK L. EDMANDS.

Copies of this patent may be obtained for five cents each, by addressing the "Commissioner of Patents, Washington, D. C."

It is hereby certified that in Letters Patent No. 1,132,978, granted March 23, 1915, upon the application of Arthur L. Russell, of Hyde Park, Massachusetts, for an improvement in "Heel-Lasting Machines," errors appear in the printed specification requiring correction as follows: Page 7, line 85, claim 7, for the word "grippers" read *gripper*; page 9, line 47, claim 24, for the word "be" read *the*; page 11, line 42, claim 47, for the word "openings" read *opening*; and that the said Letters Patent should be read with these corrections *therein* that the same may conform to the record of the case in the Patent Office.

Signed and sealed this 12th day of October, A. D., 1915.

[SEAL.]

Cl.1—22

R. F. WHITEHEAD,

Acting Commissioner of Patents.
